DANIEL M. ROTHENBERGER, OF LEESPORT, PENNSYLVANIA, ASSIGNOR TO DEVLIN W. DORMER, OF READING, PENNSYLVANIA

SANITARY BURIAL-CRYPT VENT

Application filed November 12, 1929. Serial No. 406,633.

The chief purpose of the present invention is to provide a sanitary crypt vent which will surely and thoroughly disinfect gases and fumes escaping from a burial crypt.

The assemblage of large numbers of burial crypts into mausoleums has created a new problem in sanitation. The crypts generally are placed above the ground level so that fumes and gases escaping therefrom go into the open air. Some of the crypts will be used and bodies placed therein while other crypts may be left vacant for long periods. Large numbers of people may assemble at the mausoleum for funerals and for various memorial purposes from time to time. It is essential, therefore, that the crypts and the mausoleum as a whole as well as the surrounding air be maintained clean, clear, pure and free from contaminating gases or germs. To this end constructors and operators have gone to great pains to insure that the joints and doors of the individual crypts be tightly and thoroughly sealed against exit of fumes, gases and germs. It is a scientifically accepted fact that in such a crypt in which a body has been placed there will develop from time to time noxious gases or fumes and possibly disease breeding germs. Unless some vent is allowed for the escape of these the crypt may be ruptured or an exit forced through one or more of the joints or closures. Vents have been provided leading from individual crypts into so called ventilating flues built into or associated with the mausoleums. It is a purpose of the present invention to provide such a means of communication between the crypts and the ventilating flue that an exit for gases, fumes and germs may be provided but of such character that they will be rendered harmless before being released in the ventilating flue.

A specific form the invention may take is illustrated in the accompanying drawings in which Figure 1 is a perspective fragmentary view of a portion of a mausoleum showing a sanitary vent in place in one of the crypts. Fig. 2 is a transverse vertical section through a vent in place in the crypt. Fig. 3 is a transverse horizontal section through a vent. Fig. 4 is a longitudinal vertical section

through a vent and Fig. 5 is a skeleton perspective of one end of the vent with the cover removed.

There is illustrated a ventilating flue 1 into which extends the pipe 2 leading from the vent device 3 placed on the floor 4 of a crypt preferably near its rear wall 5 against which runs the flue 1. The vent 3 has an opening 6 which may be engaged by the inner end of the pipe 2. From the opening 6 leads a channel 7 formed in the vent device 3 and this is turned at its upper end at right angles to form an outlet 8 communicating with the upper portion of the main chamber 9 of the sanitary vent device. Preferably adjacent the channel 7 and in the vent device 3 is a channel 10 having an opening near the floor of the crypt. The channel 10 passes inward into the end of the sanitary vent device 3 and turns upward at 11 to nearly the top of the device and to about on a level with the outlet 8. Here the channel 10 turns at right angles forming a horizontal portion 12 from which depends a vertical portion 13 ending in horizontal portion 14 providing an outlet into the lower portion of the chamber 9.

A cover 15 is provided for the entire device having depending side walls 16 which may be sealed in any suitable manner to the base portion of the vent 3. I have illustrated a seal packing 17 which will preferably be of jeweler's cement although any other suitable packing may be employed, or indeed in some instances the seal or packing may be omitted entirely. If desired the cover 15 may be so formed or machined as to closely and tightly fit the lower portion of the vent 3 so that the friction contact will form a sufficiently tight seal.

Within the chamber 9 is placed a suitable disinfecting material. While the character of this material is not a feature of the present invention and any suitable material may be employed I prefer to use formaldehyde in liquid form although of course when desired the crystalline form may be employed. The disinfectant preferably will be supplied in sufficient quantity to cover the opening 14 but to leave the outlet 8 uncovered. There will thus be provided a space above the dis-

infectant in the chamber 9 which space will be in direct communication with outlet 8.

The material of which the device is made is not essential for its operation. It is desirable, however, that the material throughout be such that it will not be attacked or affected by the atmosphere nor by the disinfectant nor by the noxious fumes which are to be treated. To this end the vent will preferably be made of a non-corrosive metal such as bronze, although this is not essential and any other suitable material may be employed.

When a body is placed in the crypt the crypt will be closed and tightly sealed. In this condition the only communication with the outside will be the vent 3 which has preferably been placed in the crypt when built or at least before closing and sealing. Gases or fumes forming in the crypt being relatively heavy will naturally settle to the floor and as they assemble will force their way into the duct 10 and up the portion 11 to the portion 12 which, being preferably above the level of the disinfectant in the chamber 9, will form an effective seal. The fumes passing from the portion of the duct 12 will drop through the portion 13 and exit through the outlet 14 into the disinfecting material in the chamber 9. As the gases are forced through the disinfecting material they will be purified and will rise to the upper portion of the chamber 9 which is preferably free from disinfecting material and from which leads the duct 8 through which the disinfected fumes will pass, dropping downward through the portion 7 to the outlet 6 and through the pipe 2 into the ventilating flue 1 from which they will disperse into the air. The outlet 6 is placed below the level of the disinfectant in the chamber 9 and preferably below the outlet 14 thus insuring a thorough seal.

The device may be empty when placed in position in the crypt and filled with disinfectant immediately before the body is placed in the crypt and then the cover put in place and sealed on. This may be a usual procedure and may be preferred in some arrangements. If the insertion of the disinfecting material and the assemblage of the vent is left to be done in each crypt immediately before the body is placed therein there is a possibility of the matter being neglected and one or more bodies placed in crypts in which the vent is free of disinfecting material. The device of the present invention lends itself conveniently to an avoidance of this catastrophe. When the mausoleum is built and before any of the crypts have been used the sanitary vent of the present invention may be filled to the desired extent with the selected disinfecting material and the cover placed thereon and sealed in place. When desired the vent may be charged with disinfectant and sealed at the factory. The out-

lets 6 and 10 may then be corked or otherwise suitably temporarily plugged or closed and the devices thus provided with disinfectant, shipped to be installed all at one time in all of the crypts in a mausoleum. Of course the corks or other means of sealing the ducts 6 and 10 may be removed immediately before the seals are permanently placed in position and this will obviate all possible future negligence of attention and guarantee a permanent readiness for burial. In addition to avoiding the difficulties incident to neglect or failure to fill one or more devices before bodies are placed in the individual crypts this procedure lends itself to accuracy and uniformity of procedure since the facilities for filling and sealing the covers on to the vents at the factory may be more complete and more perfect than the facilities available at any mausoleum. The outlet pipe 2 may be put in place when the mausoleum is built and when the vent is placed in the crypt the inner end of the pipe 2 may be inserted in the opening 6 and suitably sealed therein as a part of the apparatus. To facilitate this procedure, if desired the inner end of the pipe 2 may be flexible or may be suitably bent as illustrated in Fig. 2 to readily and conveniently engage the adjacent outlet 6.

The cover 15 with its depending sides 16 substantially insures against evaporation and dissipation of the disinfecting material and likewise the circuitous paths for the inlet of the noxious fumes and the outlet for the disinfected fumes reduces to a minimum the tendency to dissipate the disinfecting material.

While I have described in detail the device illustrated it is but one example of the form my invention may take. It will be understood, therefore, that neither shape, size, material nor form is essential to the invention but these and other details may be varied in any other suitable or desired manner.

I claim as my invention:

1. A sanitary burial crypt vent made of non-corrodible material and comprising a chamber within the crypt, a disinfecting fluid in the chamber, a space in the chamber above the liquid, a duct leading from the space to a point below the liquid level and through the wall of the crypt to a ventilating flue, a duct having an opening in the outer wall of the chamber and in the crypt and leading to a point above the liquid level and provided with an outlet within the chamber and below the liquid level, and a cover for the chamber extending down its sides and sealing it.

2. A sanitary burial crypt vent made of non-corrodible material and comprising a chamber within the crypt, a disinfecting fluid in the chamber, a space in the chamber above the liquid, a duct leading from the space to a point below the liquid level and through the wall of the crypt to a ventilating flue, a duct

having an opening in the outer wall of the chamber and in the crypt and leading to a point above the liquid level and provided with an outlet within the chamber and below the liquid level, a cover for the chamber extending down its sides and means for sealing the cover onto the chamber.

3. A sanitary burial crypt vent made of non-corrodible material and comprising a closed chamber within the crypt, a disinfecting fluid in the chamber, a duct leading from the upper part of the chamber above the fluid level through the wall of the crypt, and a duct having an opening in the lower part of the outer wall of the chamber in the crypt and provided with an outlet within the liquid in the lower part of the chamber.

4. A sanitary burial crypt vent comprising a closed chamber within the crypt, a disinfecting fluid partially filling the chamber, a duct leading from a point in the chamber above the liquid level to a point below the liquid level and through the wall of the crypt, and a duct having an opening in the outer wall of the chamber in the crypt and provided with an outlet within the chamber below the liquid level.

5. A sanitary burial crypt vent comprising a chamber within the crypt, a disinfecting fluid partially filling the chamber, a duct leading from a point in the chamber above the liquid level to a point below the liquid level and through the wall of the crypt, a duct having an opening in the outer wall of the chamber in the crypt and provided with an outlet within the chamber below the liquid level, a cover for the chamber, and means for sealing the cover onto the chamber.

6. A sanitary burial crypt vent comprising a chamber within the crypt, a disinfectant therein, a space in the chamber above the disinfectant, a duct leading from the space to a point below the disinfectant level and through the wall of the crypt to a ventilating flue, a duct having an opening in the outer wall of the chamber and in the crypt and leading to a point above the disinfectant level and provided with an outlet within the chamber and below the disinfectant level, a cover for the chamber extending down its sides, and means for sealing the cover onto the chamber.

7. A sanitary burial crypt vent comprising a closed chamber within the crypt, a disinfectant partially filling the chamber, a duct leading from the upper part of the chamber above the disinfectant level through the wall of the crypt, and a duct having an opening in the lower part of the outer wall of the chamber in the crypt and provided with an outlet within the disinfectant in the lower part of the chamber.

DANIEL M. ROTHENBERGER.
